UNITED STATES PATENT OFFICE.

PEARL I. GREENLEAF, OF FARMINGTON, IOWA.

REFLECTOR.

1,287,968.

Specification of Letters Patent. Patented Dec. 17, 1918.

Application filed January 12, 1918. Serial No. 211,578.

To all whom it may concern:

Be it known that I, PEARL I. GREENLEAF, a citizen of the United States, residing at Farmington, in the county of Van Buren 5 and State of Iowa, have invented certain new and useful Improvements in Reflectors; and I do hereby declare the following to be a full, clear, and exact description of the invention, such as will enable others skilled 10 in the art to which it appertains to make and use the same.

This invention relates to reflectors, and more particularly to a light reflector for blinding chicken hawks or similar birds to 15 frighten them and prevent their approach to domestic fowls.

The object of the invention is to provide a reflector for this purpose, which includes a pyramidal reflector the sides of which are 20 constructed of mirrors and which reflector has a supporting member attached to the apex thereof for supporting the reflector to permit of rotation thereof under the action 25 of air currents and further to mount a ring within the reflector which has a plurality of 30 bells pendants supported therefrom which jingle or ring during the rotary movement of the reflector and will effectively frighten hawks or similar birds of prey; should they

approach the device, at night.

With the foregoing and other objects in view this invention consists in such novel features of construction combination and arrangement of parts as will be hereinafter 35 more fully described illustrated in the accompanying drawings and claims.

In describing the invention in detail, reference will be had to the accompanying drawings wherein like characters designate 40 like and corresponding parts throughout the several views and in which:—

Figure 1 is top plan of the improved reflector.

Fig. 2 is a side elevation of the reflector. 45 Fig. 3 is a vertical section of the line 3—3 of Fig. 1, and

Fig. 4 is a side elevation of a modified form of support for the reflector.

Referring more particularly to the drawings, 50 1 designates the pyramidal reflector which is hollow and composed of a plurality of triangular reflector plates or mirrors 2, the apices of which converge to form the apex of the pyramidal reflector. A ring 3 is attached at the apex of the reflector and a suspending chain 4 is connected to the ring

3 for suspending the reflector from any suitable support, so as to permit limited rotation of the reflector under the action of air currents.

A ring 5 is positioned within the interior of the pyramidal reflector 1 a short distance below the apex thereof and this ring has a plurality of hooks 6 attached thereto at spaced intervals and depending therefrom. 60 Chains or suitable flexible supporting members 7 are connected to the hooks 6 and they have bells 8 attached to their lower ends which will jingle or ring during the movement of the reflectors and will frighten 65 hawks or similar birds of prey, when it is dark or at night and the reflector plates 2 are not reflecting sufficient light to blind or frighten the birds.

The mirror plates 2 have their reflecting 70 surfaces positioned outwardly for reflecting the suns rays or light to blind and frighten the hawk.

In Fig. 4 of the drawings, a modified form of support is illustrated, which support comprises a pin 10 the lower end 11 of which is sharpened for driving into a post 12. The pin 10 is provided with a substantially conical head 13 having its base 14 positioned upwardly to form a surface to be struck by 80 a hammer for driving the pin into the post 12. The pin 10 is further provided with a spherical enlargement 15 formed at the lower portion of the head 13, which spherical portion forms a support for the reflector 90 indicated in dotted lines and by the numeral 16. The spherical head supports the reflector 16 to permit of rotation of the reflector under action of air currents. The reflector 16 is made identical with the reflector 95 1 in all respects with the exception of the attaching ring 3 which is eliminated in a modified form and an opening is provided at the apex of the modified form for extending about the neck 17 which connects the 100 spherical portion 15 and the substantially inverted conical head 13.

In reducing the invention to practice, certain minor features of construction combination and arrangement of parts may necessitate alteration to which the patentee is entitled provided such alterations are comprehended within the scope of what is claimed.

What is claimed is:

1. A reflector for frightening hawks comprising a hollow pyramidal body composed

2
of a plurality of mirrors having their reflecting surfaces positioned outwardly, a ring carried at the apex of said body, and a flexible suspending member connected to said 5 ring, a ring positioned within said reflector a short distance downwardly from the apex thereof, and audible signaling means carried by said ring.

2. A reflector for frightening hawks comprising a hollow pyramidal body composed 10 of a plurality of mirrors having their reflecting surfaces positioned outwardly, means engaging said body at the apex for support-

ing the body to permit rotation thereof under the action of air currents, a ring positioned 15 within said body a short distance below the apex of the same, a plurality of pendant flexible supports connected to said ring, and bells attached to the lower ends of said flexible supports.

In testimony whereof I affix my signature in presence of two witnesses.

PEARL I. GREENLEAF.
